TIP FOR GAS-BURNING APPARATUS

Application filed July 28, 1924. Serial No. 728,571.

This invention relates generally to apparatus for brazing, cutting, welding or otherwise treating metals by means of jets of gases directed upon the work, and particularly to a tip for such apparatus.

The apparatus with which the improved tip disclosed herein is intended for use is designed more especially for burning oxygen and acetylene under pressure and is commonly known as an oxyacetylene torch or blowpipe. In the most common form of the apparatus suggested above oxygen and acetylene are directed through a common passageway or through separate passageways to a tip at the discharge end of which these gases burn, producing a flame of very high temperature. Prior to this invention most of the oxygen necessary to support combustion of the combustible passed through the torch or blowpipe from a container, and it is of course apparent that the provision of this container of oxygen added to the expense of operating the apparatus. The flame which issues from the tip of an oxyacetylene torch or blowpipe is coneshaped and of considerable diameter, and it is therefore impossible for very much oxygen which is in the atmosphere to penetrate the flame so as to supply some of the oxygen which a flame requires to be sustained.

The purpose of the present invention is to provide a tip for oxyacetylene torches or blowpipes which has an orifice of such shape that much greater area of the flame is exposed to the atmosphere and a much thinner flame is produced, whereby instead of most of the oxygen being supplied from an artificial source a large portion of said oxygen is collected from the atmosphere which surrounds the flame. This arrangement results in a great saving in the cost of operating the apparatus, for the reason that the amount of oxygen drawn through said apparatus from the container associated therewith is greatly reduced.

With the foregoing and other objects in view, the invention comprises the novel construction, combination and arrangement of parts hereinafter more specifically described and illustrated in the accompanying draw-

ings, wherein is shown the preferred embodiment of the invention. However, it is to be understood that the invention comprehends changes, variations and modifications which come within the scope of the claims 55 hereunto appended.

Fig. I is a section of our improved tip associated with a fragment of the head of the oxyacetylene torch.

Fig. II is an end elevation of the tip 60 shown in Fig. I.

Fig. III is a cross section on line III—III of Fig. I.

Fig. IV is a section of the form of tip used with an apparatus wherein the oxygen 65 and acetylene are caused to flow through separate passageways.

Fig. V is an end elevation of the tip shown in Fig. IV.

Fig. VI is a cross section on the line 70 VI—VI of Fig. IV.

Figs. VII, VIII, and IX illustrate tips provided with orifices of various shapes.

In the drawing, A designates the discharge head of an oxyacetylene torch or blowpipe, 75 which head is provided with a passageway B terminating in an enlarged internally threaded portion C. 1 designates our improved tip which is provided with a passageway 2 formed therethrough, which passageway is in communication with the passageway B, said tip also being provided with a reduced externally threaded portion 3 adapted to be screwed into the internally threaded portion C whereby said tip is secured to the head A. The tip 1 is provided with a non-circular portion 4 whereby it may be rotated to screw said tip into the head A, and said tip is also provided with a seat 5 adapted to contact closely with a seat 6 formed on the head A whereby fluid-tight contact is obtained between said head and said tip.

By referring to Fig. I of the drawings, it will be noted that the passageway 2 is of 95 approximately the same diameter from the inner end of the tip 1 to a point which is slightly removed inwardly from the outer end of said tip, which point is designated by the reference character X in Fig. I. The 100

cross sectional shape of that portion of the passageway just referred to is circular, as shown in Fig. III. However, from the point X to the outer end of the tip 1 the passageway is cross-shaped in cross section, as shown in Figs. II and III, this portion of the passageway being designated by the reference character 2'.

In the operation of a torch or blow-pipe provided with our improved tip the combustibles will flow through the portion 2 of the passageway in the form of a body circular in cross section. When, however, said combustibles reach the point X and pass through the portion 2' of said passageway, the cross sectional shape of said body of combustibles will be caused to conform to the shape of the passageway 2', which in Fig. I is cross-shaped. This will cause a stream 10 of combustibles which is cross-shaped in cross section to flow from the discharge end of the tip 1, and because of the shape of said stream of combustibles it is quite apparent that when said stream of combustibles 15 is burning much greater area of the flame is exposed to the atmosphere through which said flame passes than if said stream of combustibles were circular in cross section. Because of this much more oxygen will be 20 collected from the atmosphere than was collected heretofore by the circular flames. In addition to the fact that greater area of flame is exposed to the atmosphere it will be apparent that the flame will be so shaped 25 that there will be no thick portions thereof, and as a result the oxygen in the atmosphere may penetrate the flame and thus produce a complete and proper mixture of oxygen and acetylene to obtain a flame of the 30 desired temperature.

In Fig. IV a tip is illustrated which is intended for use with a torch or blowpipe having separate passageways for the oxygen and mixed gases. In the view referred to, 35 A' designates the head of the torch or blowpipe, which is provided with an oxygen conduit D and a mixed gas conduit E. 1' designates a tip which is fixed to the head A' by means of a coupling member 7. The 40 tip 1' includes an oxygen conductor 8 having a passageway 9 communicating with the conduit D in the head A', said conductor being extended from said head A' to the outer end of the tip 1'. The tip 1' is of consider- 45 ably larger diameter than the conductor 8, so that an annular space 10 is provided around the conductor 8. The annular space 10 communicates through the medium of a plurality of openings 11 with a second an- 50 nular space 12, which space 12 in turn commu- 55 nicates with the mixed gas conduit E in the head A'. The annular passageway 10 is provided at its outer end with a portion 10', which is cross shaped in cross section, 60 said portion 10' being similar in shape to

the portion 2' of the tip illustrated in Fig. I.

In the operation of the apparatus shown in Fig. IV, some oxygen flows through the conduit D and through the opening 9 in the conductor 8 to the discharge end of the tip 1' as required. Also, mixed gases flow through the conduit E, through the annular space 12 and openings 11 to the annular space 10. The mixed gases then pass through the portion 10' of the annular space 10, and because of the shape of said portion 10' a stream of mixed gases is caused to issue from the tip, which is cross-shaped in cross section. It is, of course, apparent that the same advantages will result from the use of a flame cross-shaped in cross section in connection with the tip shown in Fig. IV as will result from a flame of that shape in connection with the tip shown in Fig. I.

In connection with the structures shown in Figs. I and IV we have stated that the tips are provided with cross-shaped orifices, but it is plain that orifices of other shapes may be used. In Figs. VIII, IX and X we have illustrated some of the orifices which may be used and which will have all of the advantages that the cross shaped orifice has.

It will be noted that the discharge portions of the tips illustrated in Figs. I and IV are tapering, and the purpose of this is to produce a cone-shaped flame.

Another advantage of our improved tip over the ordinary tip provided with a round orifice results from the fact that a flame issuing from our tip will not have such force as to prevent the metal being treated from flowing to the heated area, as will the flame issuing from a round orifice.

We claim:

1. A welding tip for a gas-burning apparatus comprising a tubular member provided with a passageway formed therethrough from end to end thereof, said passageway at the discharge end of said member being provided with inwardly extended, circumferentially spaced radial extensions formed in the wall of said member and extended approximately parallel with the major axis thereof, which give to said passageway at said discharge end of said member a shape non-circular in cross-section each portion of which communicates with all other portions thereof.

2. A welding tip for a gas-burning apparatus comprising a tubular member provided with a passageway formed therethrough from end to end thereof, said passageway being smooth throughout the greater portion of its length and at the discharge end of said member said passageway being provided with inwardly extended, circumferentially spaced radial extensions formed in the circumferential wall of the member and

extended approximately parallel with the major axis thereof, which give to said passageway at said discharge end of said member a shape non-circular in cross-section each portion of which communicates with all other portions thereof.

3. A tip for a gas-burning apparatus comprising a tubular member provided with a passageway formed therethrough from end to end thereof, said passageway at the discharge end of said member being provided with inwardly extended, circumferentially spaced radial extensions formed in the wall of said member and extended approximately parallel with the major axis thereof, which give to said passageway at said discharge end of said member a shape non-circular in cross-section each portion of which communicates with all other portions thereof, and a conductor arranged within the passageway in said member and extended longitudinally thereof, the outer diameter of said conductor being less than the diameter of the passageway formed through said member.

In testimony that we claim the foregoing we hereunto affix our signatures.

ARTHUR J. FAUSEK.
IRWING F. FAUSEK.
